UNITED STATES PATENT OFFICE.

HENRY P. HAMILTON, OF TWO RIVERS, WISCONSIN.

DESIGN FOR A FONT OF TYPE.

SPECIFICATION forming part of Design No. 37,308, dated January 31, 1905.

Application filed November 17, 1904. Serial No. 233,224. Term of patent 7 years.

To all whom it may concern:

Be it known that I, HENRY P. HAMILTON, a citizen of the United States, and a resident of Two Rivers, in the county of Manitowoc and State of Wisconsin, have invented a new, original, and ornamental Design for a Font of Type, of which the following is a specification, reference being had to the accompanying drawing, forming part thereof.

The drawing illustrates an impression of the characters of a font of type of my design.

I claim—

The ornamental design for a font of type, as shown.

HENRY P. HAMILTON.
